UNITED STATES PATENT OFFICE.

ELIZABETH MERRILLEES, OF MELBOURNE, VICTORIA.

COMBINED CORSET AND ABDOMINAL BELT.

SPECIFICATION forming part of Letters Patent No. 639,078, dated December 12, 1899.

Application filed June 9, 1898. Serial No. 683,032. (No model.)

To all whom it may concern:

Be it known that I, ELIZABETH MERRILLEES, stationer, a subject of the Queen of Great Britain, residing at No. 224 Swanston street, 5 Melbourne, in the British Colony of Victoria, have invented an Improved Combined Corset and Abdominal Belt, of which the following is a specification.

This invention has been designed for the 10 purpose of providing a combined corset and abdominal belt in which the whole of the beneficial effects of abdominal belts are retained and in which the pressure arising from the use of such belts is sustained by the sacrum instead of being concentrated over or constricting the region of the kidneys, as hitherto.

It consists in providing a properly-fitting long corset the back of which must extend to 20 the lowest part of the sacrum and should for the purpose of giving a proper and comfortable fit have inserted in it on each side of the lacing parallel strips of whalebone, two only of which should reach to the bottom of the 25 corset, the others stopping short at a gusset let into each side, so as to fit comfortably over the hips. By this means the weight of the abdomen is transmitted through the belt and is supported from the sacrum, thereby avoiding 30 pain or injury to the kidneys or other movable parts of the abdomen and so overcoming one great objection to the use of ordinary combined corsets and belts. To the lower part of this corset an abdominal belt, 35 constructed as hereinafter described, is attached by sewing or suitable fastenings. The precise point of attachment may vary somewhat; but it should be at that part of the corset which covers the back of the hips and in 40 a line with the sacrum. The belt should be made in three parts—viz., two end pieces and a center piece—and it must be long enough to pass around and comfortably support the abdomen. The center piece should not extend 45 upward beyond the two end pieces, because if it does so the beneficial effect of the belt will be lost—that is to say, the center piece will not in that case support the abdomen, but will merely press upon and flatten the 50 stomach. It should be made mainly of a non-elastic material—such, for instance, as corded silk—with a gusset of elastic material let into each length. The center length must be and

is connected to the two side lengths by suitable fastenings, by which the belt itself can 55 also be regulated so as to fit the abdomen. In order to prevent the belt rising above the required position in front, I provide two retaining-hooks, one at each side of the front of the lower end of the corset, so as to prevent 60 the belt rising above them.

Referring to my drawings, Figure 1 represents a front view of my invention on the person of the wearer. Fig. 2 also represents a front view of my invention on the person, but 65 with the belt unfastened. Fig. 3 represents a back view of my invention.

A is the non-elastic material of the belt; B, the elastic gussets; C, the laces, and D the retaining-hooks on the lower part of the front 70 of the corset.

E E are the strips of whalebone, and G G the gussets for the hips.

I am aware that other inventions of a somewhat similar character have been invented 75 before, but not one that effects the main object of my invention, which is to support the abdomen and direct the pressure arising from such belts onto the sacrum.

Having now particularly described and ascertained the nature of my said invention and in what manner the same is to be performed, I declare that what I claim is—

As a new article of manufacture, a combined corset and abdominal belt, consisting 85 of a corset having its back extending to and terminating at the lowest point of the sacrum and its front provided with hooks, and an abdominal belt made in three parts, the two side parts being sewed on opposite sides of 90 the back to the part of the corset which covers the back of the hips in line with the sacrum, and being provided with elastic gores, and the central part provided with means whereby it may be attached to the forward 95 ends of said side parts, adapted to engage said hooks to prevent the rising of the same, and provided with an elastic gore, the said belt overlying the outside of said corset from its points of attachment around to the front, 100 and serving to support the abdomen from the sacrum.

ELIZABETH MERRILLEES.
